COMPENSATOR AND METHOD

George Washington Pierce, Cambridge, and Atherton Noyes, Jr., Winchester, Mass.; said Noyes assignor to said Pierce

Application June 30, 1933, Serial No. 678,482

5 Claims. (Cl. 177—386)

The present invention relates to vibratory methods, systems and apparatus, and more particularly to electrical systems and apparatus employing electromechanical vibrators. From a more limited aspect, the invention relates to the transmission and reception of intelligence, using sound waves as the agency of communication, and is an improvement upon the invention illustrated and described in application Serial No. 10 684,200, filed August 8, 1933. The term "sound" will be employed hereinafter, in the specification and the claims, to include the supersonic, as well as the audible part of the sound spectrum, and to include also all kinds of elastic vibrations. The invention, indeed, finds particular application to supersonic communication.

The primary object of the invention is to provide a new and improved compensator for the transmission and reception of sound in any selected direction.

20 A further object of the invention is to provide a directionally selective transceiver for submarine communication and direction finding which can be permanently fixed in position and which operates without the necessity of bodily rotation.

With the above ends in view, a feature of the invention resides in the use of a number of small transducers, disposed side by side, having individual radiating faces, and with magnetostrictive windings slidable along magnetostrictive wires attached to the individual transducers.

Other and further objects will be explained hereinafter, and will be particularly pointed out in the appended claims.

35 The invention will now be explained in connection with the accompanying drawings, in which Fig. 1 is a plan of a preferred embodiment of the improved compensator of the present invention; Fig. 2 is a fragmentary plan of the same, upon a larger scale; Fig. 3 is a broken, enlarged, longitudinal section, taken upon the line 3—3 of Fig. 1, looking in the direction of the arrows; Figs. 4 and 5 are further enlarged, transverse sections, taken upon the lines 4—4 and 5—5 of Figs. 2 and 6, respectively, looking in the directions of the arrows; Fig. 6 is a fragmentary plan similar to Fig. 2, showing the parts in relatively different positions; Fig. 7 is a view 40 of a modification; and Fig. 8 is a section, taken upon the line 8—8 of Fig. 7, looking in the direction of the arrows.

50 A plurality of transducers 1, 2, 3 . . . 13, are each mechanically connected with a wire core 16, 55 17, . . . 28, preferably of nickel, nickel-steel,

nickel-copper, nickel-cobalt, chrome-nickel, chrome steel, or of any other metal element or alloy characterized by comparatively large magnetostrictive effects. The cores are parallel to one another, and each is shown positioned substantially in axial alignment with, and magnetostrictively coupled to, a picked-up coil 50, as a suitable mechanism for obtaining electric current or voltage from the mechanical vibrations of the cores 16 to 28, or vice versa. The coils 50 are shown connected together in series by flexible conductors 101 and 200, but may, of course, be connected in parallel, or in any series-parallel combination, as desired. The coils 50, which interact magnetostrictively with the cores 16 to 28 to develop voltages in the coils in response to vibrations in the cores and to produce vibration of the cores by the action of the magnetic field produced by current in the coils, will be referred to, in the specification and the claims, under the broad heading of interactors. An interactor may here be defined broadly as a device permitting and causing the interaction of mechanical vibrations with electric currents and voltages for the transformation of energy from one form to the other. The voltage or current developed may be fed from, or into, an oscillator or receiver 42, the former for transmission purposes and the latter for reception. The oscillator may serve as a source of high-frequency, electric oscillations for producing the mechanical vibration in the wires 16 to 28, and may be of any desired type, such for example, as is illustrated and described in United States Letters Patent 1,750,124, issued March 11, 1930.

30 35 Polarizing magnets (not shown) may be employed in connection with the magnetostrictive wires 16 to 28 or, preferably, the polarizing field may be obtained by passing a direct current through the pick-up coils 50.

The oscillator or receiver 42 is tuned, as by 40 means of tuning condensers (not shown), to the same frequency as the frequency of the sound-beam signal, or to a desired component of the sound frequency.

The transducers 1 to 13 are provided with 45 their faces lying in a plane and along a line of length sufficient, in relation to the wave length of sound in the medium, to give sharp directional discrimination. The spacing between centers of adjacent transducers should not be greater than one half-wave length of sound in 50 the medium at the highest frequency to be employed. Otherwise the compensator will have multiple angles of response.

The transducers 1 to 13 may be fewer or more in number than illustrated, and may be of any desired form, the conical form forming the subject matter of Patent No. 2,044,807. The sound 5 is radiated to or from the large end of the cone, the magnetostriuctive core 16 to 28 that drives it, or that is driven by it, being secured to the small end. For reception and transmission of sounds of any desired frequency, particularly high frequencies, through the water or other elastic media, the large ends of the transducers 1 to 13 will be submerged in the ocean. According to the preferred arrangement, the transducers are shown disposed side by side, but out of contact 10 with one another, at uniform intervals along a substantially straight line, attached to a common supporting base 58, which may be the side of a ship, and with their larger ends facing in a common, predetermined direction.

20 The array of transducers may be in a single line, as illustrated in Fig. 1, in which case the compensator will have good directional selectivity for signals arriving at angles lying in the plane of the paper, but substantially no selectivity for signals arriving at angles lying in a plane perpendicular to the plane of the paper. If it is desired, as in the case of communicating 25 between ships, to transmit or receive most efficiently in the plane of the paper, it will be necessary to give the array of transducers a dimension 30 perpendicular to the plane of the paper large in comparison with the wave length employed. This may be done by forming the array of a number of parallel, linear arrays, with the faces of the transducers all lying in the same perpendicular plane, as shown in Fig. 7, and in cross section in Fig. 8. Corresponding units of the linear arrays should 35 then be joined by sound conducting wires, of equal length, to the appropriate retarding wires 16 to 40 28.

A composite, acoustic-energy converter is thus provided, having a large number of transducers 1 or 13, all separated from one another, yet all free to vibrate to produce a common, enhanced effect. 45 The transducers, of course, may be more or fewer in number than here illustrated. The arrangement of the coils permits of their proper positioning to take advantage of the various cooperative effects of the vibrator wires 16 to 28. In 50 reception, assuming, for example, a beam of particular, high-frequency sound, modulated or unmodulated, below and to the right of Fig. 1, the incident sound beam, directed, for example, from a distant sending station (not shown) at an angle 55 to the line of transducers 1 to 13, located at a receiving station, such as a ship, will impinge on the transducers 1 to 13 in numerical order, beginning with the lowermost transducer 1. The transducers will all become excited into vibration, 60 in numerical sequence. Mechanical vibrations will, first, begin to travel along the wire 16, connected with the lowermost transducer 1, toward its coil 50, before they do so in the wire 17, connected with the next transducer 2, and so on. 65 By the time that the sound impulse has reached the last transducer 13, the mechanical vibrations will have traveled along the wire 16 a predetermined distance, along the next wire 17 a smaller distance, along the wire 18 a still smaller distance, 70 and so on. The wires 16 to 28 thus serve as retardation wires for transmitting a particular, selected frequency of mechanical vibration. If the coils 50 are so axially adjusted along the retardation wires 16 to 28 that the mechanical vibrations, traveling along the wires, shall be so re-

tarded as to reach the various coils 50 at the same moment, the coils 50 will operate in synchronism to convert the mechanical vibrations, by magnetostriiction, into electrical energy, thereby to produce an enhanced effect as to intensity. 5

The sound impulses will thus add together at the coils 50, positioned to receive this signal as a maximum and connect it into an electrical voltage which is fed into the receiver 42. Sound impulses from other sources, having a different orientation with regard to the array, will arrive out of phase with each other at the coils 50 and add to give a zero or very weak combined signal.

Similar considerations will apply for transmission, the sound impulses leaving the transducers 1 to 13 at adjustable time intervals in similar manner and thereby combining to produce a beam of sound which may be rotated at will by adjustment of the angular position of the line of coils 50. 20

This arrangement is an important element in a direction finder. As the line of coils 50 occupies a given angle, corresponding to maximum response to a given direction of the sound beam in the medium, it is possible to determine the direction of the sound beam; and as departure from the said angle carries with it a smaller degree of response, it is possible to obtain a very sharp determination of direction. The invention finds also many other uses, such as range finding. 30

If the transducers 1 to 13 are arranged at equal intervals along a straight line, the sound waves will, of course, arrive at the transducers at successive, equal time intervals apart. In order that the coils 50 may reinforce one another, they 35 should be spaced along the magnetostriuctive cores 16 to 28 at proper intervals apart, along a substantially straight line, the inclination of which, to the sound beam, will vary with the direction of the sound beam to be transmitted or received. 40 In reception, for example, the angle of the line of coils 50 should be such that the coils 50 shall be energized in phase. If the sound happens to be incident normal to the array of transducers, the apparatus will give maximum response when the 45 line of coils is parallel to the line of transducers. If the incident sound arrives from any other direction, maximum signal will be obtained when the line of coils is so positioned that the time of arrival of any given sound pulse, suitably retarded 50 in each of the wires 16 to 28, is the same at all the coils 50.

The impulses received at different instants at a number of sound receivers are thus delayed in such manner as to bring all the separate impulses together at a common listening point at the same instant. From the period of delay introduced in each of the various lines, the angle of incidence of the sound is determined. Compensating devices have heretofore been operated at low, 60 audible frequencies, and the retardation has been introduced, for example, electrically, or by means of speaking tubes of variable lengths. The present invention deals with new and improved apparatus, employing wires or small tubes as sound 65 conductors for obtaining the desired retardations. Longitudinal sound vibrations in these wires travel with constant velocity from the terminal unit 1 (say) to coil 50, and the time retardation introduced in this wire, therefore, is directly proportional to the length of wire lying between the transducer 1 and its coil 50. 70

It is very important, in any type of compensator, to prevent reflections of energy from the ends of the retardation lines. In other words, 7

sound energy, passing by the coil 50 and arriving at the end of the wire, must not be allowed to reflect and return a second time to the coil. If this occurs, a standing wave system is set up in the wire and the net result is that for any coil setting the compensator, instead of responding to sounds from one direction only, responds equally to sounds arriving from two directions making equal angles with the normal to the array of transducers, and on both sides of this normal.

We have found it convenient to prevent such reflection by enclosing the ends of the wires 16 to 28 tightly in a soft rubber sleeve 34 a foot or so in length, which absorbs and dissipates any sound energy reaching it.

When magnetostrictive tubes are used in place of wires, damping may be more effectively obtained by applying a viscous substance, such as rubber, both internally and externally, so that more of the surface of the tube is acted upon. The internal friction may be obtained by forcing a soft rubber rod of normally greater diameter than the magnetostriction tube into the end of the tube and allowing it to expand against the walls of the tube. Additional rubber may then be wrapped tightly around the outside of the tube.

The principle of the operation having thus been explained, the illustrated embodiment will now be described, in detail.

The transducers 1 to 13 are attached to the base 58 by means of bolts 14, passing through flanges 15, that are separated from the larger ends of the transducers by very thin webs 29 (Fig. 3), in such manner as not to affect the vibrations of the transducer. One end of each of the wires 16 to 28 is secured to the small end of the corresponding transducer and the other end is provided with a tension spring 30 that is held, by means of a bolt 31, to an upright 32. The wires 16 to 28 are thus held taut and straight, parallel to one another, as shown in Fig. 1. The uprights 32 are shown positioned at varying points of a base member 33. The exact position of the upright 32 is not important since the said other ends of the wires 16 to 28 are damped in any suitable manner, as by means of the sleeves 34, so that no appreciable energy is reflected at these ends.

The wires 16 to 28 may very well be replaced by self-supporting tubes of small diameter, in which case the tension springs may be omitted. With either construction, it is important to provide sufficient clearance at the axes of the coils 50 so that the coils shall not, as they move, rub on the wires or tubes. Such rubbing of the coils on the sound conductors produces disturbing noise.

It will be understood that, throughout the specification and the claims, the term "wire", as applied to a sound-conducting member, shall apply also to tubes of small diameter.

Underneath each straight wire or tube 16 to 28, and parallel thereto, there is disposed a straight guide track 35, fastened to the base member 33 in any desired manner, as by bolts or screws 36. The tracks 35 are spaced from the base by spacing members 37, in order that members 38, for carrying or supporting the coils 50, may readily be slidably mounted thereon. Sliding movement of the members 38 upon their tracks 35, therefore, renders it possible to adjust the coils 50 along the wires 16 to 28. The corresponding, immediately disposed, coil-supporting member, over the wire 22, indicated at 49, is held fixed, against movement, by a bolt 51, as shown in Fig. 5. The

mechanism will now be described for adjusting the coils 50 as a unit, so that they may always lie in a straight line, suitably inclined to the wires 16 to 28 and, therefore, to the line of transducers 1 to 13.

Referring more particularly to Fig. 4, the lower wall of the support 38 is countersunk at 39 to receive the head 40 of a bolt 41. The bolt 41 extends freely upward through an opening 43 in the upper wall of the support 38, and that communicates with the countersink 39. A nut 44 holds a flanged, bearing sleeve 45 securely in place on the bolt 41. A second bearing sleeve 46, mounted over the sleeve 45, between its end flanges, is provided with an intermediate disposed flange 47. Links 48 of a pantograph are pivoted about each bearing sleeve 46, above and below the flange 47. The links 48 are pivoted to each other at 69 (Fig. 6). As the pantograph links 48 are collapsed or extended, therefore, the coil-supporting members 38 are caused to slide along their tracks 35.

The slides 38 are thus caused to move, back and forth, along a diagonally disposed, straight line that always passes through the bolt 51 (Figs. 1 and 5). The range of movement, both longitudinally and transversely, may be greater than is illustrated in Fig. 1. An index 52, that is fast to one of the slides 38, shown as the lowermost slide, may cooperate with a scale 53 to measure the angle through which the coils have been rotated, or it may read directly the angle of the beam relative to the line of the transducers 1 to 13.

Each coil 50 is mounted between insulating plates 54, provided with openings 55 through which the magnetostrictive wires 16 to 28 extend. An upward extension 56 of the bolts 41 and 51 passes through one of the insulating plates 54, that is held on the extension 56 by a nut 57. Binding posts 58, moulded into the insulating plates 54, connect with the ends of the coils 50 and are connected with successive coils by the conductors 101 (Fig. 6).

It has been found convenient to make electrical connection to the coils 50 at the central coil, which does not move. The series circuit, as at present used, thus begins at the central coil 50, passes through half the coils, by way of the flexible connectors 101, to one end of the pantograph, then returns, via the flexible conductor 200, mounted on the pantograph, to the other end of the line of coils, and returns through the remaining coils and the leads 101 to the center again.

One end of a cable 78 is fastened at 59 to the left-hand side of the lowermost slide 38, as viewed in Fig. 1. The cable 78 extends over an idler pulley 60, an actuating pulley 61 and an idler pulley 62, to the uppermost slide 38, to which it is fastened at 72. A second cable 63, fastened at one end to the said uppermost slide 38 at 64, passes over idler pulleys 65 and 66, and its other end is fastened to the lowermost slide 38 at 67. The actuating pulley 61 may be manipulated by a handle 68 to expand and contract the pantograph.

Modifications will obviously occur to persons skilled in the art, and all such are considered to fall within the spirit and scope of the invention, as defined in the appended claims.

What is claimed is:

1. In a system of parallel retardation paths, each comprising a linear transmission member and each equipped with vibratory terminal apparatus for intercommunicating energy with a

sound-conveying medium and each equipped with an interactor variably positionable along said linear member, with a phase in said transmission member at said interactor relative to the 5 terminal phase in said member determined by the position of said interactor along said member, means for simultaneously varying the positions of the several interactors along their several 10 transmission members and maintaining a substantially straight-line, spatial relation between the several interactors, said means comprising a pantograph and a system of linear guides.

2. Apparatus of the character described having, in combination, a plurality of transducers, 15 adapted to be positioned in a sound-conveying medium and to cooperate in directionally inter-communicating energy with the medium, a transmission member affixed in sound-communicating relation to each transducer, a movable interactor cooperative with each transmission member, the interactors being disposed along a substantially straight line, each of said transmission members being adapted to transmit energy along its length at a definite velocity to 20 enable each transmission member and its associated interactor to cooperate to introduce a predetermined phase displacement between transducer and interactor, and means comprising a pantograph for simultaneously adjusting 25 the interactors to predetermined positions along the several transmission members to enable the combination of interactors, transmission members and transducers, by introducing predetermined phase retardations of the said energy 30 transmitted in the several transmission members, to cooperate for directional energy communication with said medium.

3. Apparatus of the character described having, in combination, a plurality of transducers 40 adapted to be positioned in a sound-conveying medium and to cooperate in directionally inter-communicating energy with the medium, a substantially straight transmission member affixed in sound-communicating relation to each transducer, the transmission member being substantially parallel to one another, a movable interactor cooperative with each transmission member, each of said transmission members being adapted to transmit energy along its length at a 45 definite velocity to enable each transmission member and its associated interactor to cooperate to introduce a predetermined phase displacement between transducer and interactor, a substantially straight guide for each interactor, the 50 guides being substantially parallel to the transmission members, the interactors being disposed along a substantially straight line, and means comprising a pantograph for simultaneously adjusting the interactors along their respective 55 guides to predetermined positions along the several transmission members without disturbing their substantially linear relation to enable the combination of interactors, transmission members and transducers, by introducing predetermined phase retardations of the said energy 60 transmitted in the several transmission members, to cooperate for directional energy communication with said medium.

4. Apparatus of the character described having, in combination, a plurality of transducers adapted to be positioned in a sound-conveying medium and to cooperate in directionally inter-communicating energy with the medium, the 5 transducers being disposed in a plane array in parallel, linear groups, a plurality of transmission members corresponding in number to the number of said linear groups, and affixed in sound-communicating relation to the transducers, all the transducers in each of said linear groups being affixed to a single transmission member by sound-conducting members of fixed length, a plurality of movable interactors cooperative with the transmission members, each of 10 said transmission members being adapted to transmit energy along its length at a definite velocity to enable each transmission member and its associated interactor to cooperate to introduce a predetermined phase displacement between transducer group and interactor, and means for simultaneously adjusting the interactors to predetermined positions along the several transmission members to enable the combination of interactors, transmission members and 20 transducers, by introducing predetermined and interdependent phase retardations of the said energy transmitted in the several transmission members, to cooperate for directional energy 25 communication with said medium. 30

5. Apparatus of the character described having, in combination, a plurality of transducers adapted to be positioned along a substantially straight line in a sound-conveying medium in 35 which the phase of vibration of the sound is progressively different from transducer to transducer, a substantially straight transmission member affixed in sound-communicating relation to each transducer, an adjustable interactor cooperative with each transmission member, the interactors being disposed along a substantially straight line, each of said transmission members being adapted to transmit energy along its length at a predetermined velocity to enable 40 each transmission member and its associated interactor to cooperate to introduce a predetermined phase difference between each transducer and its corresponding interactor, and means comprising a pantograph for simultaneously adjusting the interactors along their corresponding transmission members, without disturbing their substantially straight-line relation, to predetermined positions such that, owing to the time of 45 travel of the energy along the transmission members between each transducer and its corresponding interactor, vibration peaks which occur at the same instant of time at the predetermined positions occur at the said progressively different 50 times at the corresponding transducers, whereby the said progressive differences in phase of vibration of the sound from transducer to transducer is compensated for or produced by the progressively different times of travel in the said transmission members between the transducers and 55 their corresponding interactors. 60 65
